UNITED STATES PATENT OFFICE

HAROLD R. HORN, OF CINCINNATI, OHIO

WEATHER STRIPPING

Application filed December 1, 1931. Serial No. 578,265.

My invention relates to weather strips for windows, doors and the like, and has for its object the provision of weather stripping which may be economically constructed, and which may be applied without reconstruction, change or removal of the window frame or sash or the door opening in which it is to be applied.

It is an object of my invention to provide a weather strip which is self-adjusting to any warping or shrinking of the sash or frame. Another object of my invention is the provision of a weather strip which will have resilient double contact between the frame and sash.

Another object of my invention is the provision of a strip which, because of the manner in which its edges are folded, reinforces the strip. It further accommodates itself inconspicuously to irregularities in the construction of the windows and doors or frames in which the strip is used.

A still further object of my invention is the provision of a weather strip which may be formed in a continuous operation with forming rollers.

I provide a spring strip having a channeled base which may be convexed so that the head of a nail may be countersunk therein, thereby minimizing the likelihood of the nail coming loose or scratching the sash. From the channel two legs extend at obtuse angles, and the end edges of the legs are folded back into surface contact with the legs thereby providing a rounded bearing surface which will allow the window or door to move with reference to the strip without being cut or gouged.

A further object of the rolling back of the edges of the legs is to provide a smooth, rounded surface which will not cut a person's fingers when the sash or frames are being cleaned. The turned back edges also reinforce the strip and permit its attachment in various positions as will be described, which make the strip adapted for use with different types of sashes and doors regardless of whether or not the seal is for a side, top, bottom, or center of the openings.

While my new strip is particularly adapted for use with double hung sliding windows, it

may also be used on the sides and tops of doors and the meeting rails, heads, centers and sills of different types of windows and doors.

The above objects and other advantages to which reference will be made, I accomplish by that certain combination and arrangement of parts of which I have shown a preferred modification.

In the drawing:—

Figure 1 is a cross section of a side of a double-hung window sash, showing the window strip in place in the guiding groove.

Fig. 2 is a cross section of the meeting rails of a double hung window, showing the window strip in place.

Fig. 3 is a cross section of the head of the frame, and the top of the upper sash of a window showing one manner of mounting the window strip.

Fig. 4 is a cross section of a door and a door frame showing a manner of mounting the strip in place.

Fig. 5 is a perspective view of a portion of a weather strip made in accordance with my invention.

The weather strip may be made of any suitable flexible spring material, such as sheet brass. Referring first to Fig. 5, I have shown a strip having a base 1, two obtuse angled legs 2, 2, extending out in a trough-like formation. The base 1 is wide enough to provide space for a nail or screw head, such as is indicated at 3 in Fig. 1. The two legs 2, 2, give double cushion spring to the strip and also afford double contact with the frame. The shape of the strip tends to hold the two outer edges 4, 4, tightly against the window sash, making a double contact with the window. Also, due to this spring tension of the material of which the strip is made, the strip is self-adjusting to any warping or shrinking of the sash or frame, due to changing weather conditions. In my preferred form the outer edges 4, 4, of the strip are rolled or hemmed by turning the edges completely over so as to lap onto themselves. These smooth rolled edges prevent the edges from cutting into the sash or frame when the window is slid up and down, and also give a rigidity to the entire strip. When washing the win-

dows, this hemmed edge prevents the cutting of the fingers.

When placing the strip in a double hung window, it is not necessary to remove the sash. The strip is merely slid between the sash 5 and the frame 6 (in Fig. 1), and nails 3 are driven in at spaced intervals along the base 1, fastening the strip to the frame. In this position of the window it is not necessary to nail the strip the full length of the strip, because the window holds the strip under tension and presses the two inside corners of the base tightly against the frame, whether it is nailed or not.

In placing the strip between the meeting rails of a double hung window, it has been found preferable to nail the strip with the legs extending toward the inner surface of the lower rail of the upper window as indicated in Fig. 2. Nails may be applied to one of the reinforced edges 4 to secure the strip to the upper part of the upper rail. Numeral 7 indicates the rail of the top window, and 8 the rail of the lower window in a double sash window. The strip is fastened by nails 3 inserted through the edge 4 of the strip in such a way that the channel 1 is pressed against the rail 8 and the opposite edge 4 is pressed against the rail 7 when the window is closed. In this construction it is possible to open and close the window without the edges of the rails catching on the strips.

In placing the strip between the top of the window sash and the frame, it has been found advisable to fasten the strip by one edge onto the sash itself, as shown in Figure 3. In this figure the strip is fastened through one edge 4 by a nail 3 to the top of the upper sash 9, so that the side of the strip nearest the nail 3 lies against the sash 9. The opposite edge 4 is pressed against the frame 10 when the upper sash is closed. This method may also be used in fastening the strip to the bottom of the lower sash between it and the sill, or any of the other methods shown in the figures may be used, such as nailing the strip to the sill, or nailing to the head of frame between top of upper sash and the frame.

When using the strip in a door, the preferred method of attachment is shown in Figure 4. The strip is fastened to the door frame 11 at one edge 4 by a nail 3, so that the flat part of the strip nearest the nail will lie flat against the door frame. The nailed edge is closest to the open edge 12 of the frame, so that when the door 13 is closed it will not catch on the strip.

It is an important feature of my invention that the strip may be nailed or screwed into position in more than one position, with the fastener in either case passing through a reinforced portion of the strip. If the strip

is attached by its base as shown in Figure 1, the angled portions where the legs branch out reinforce the strip; and if the strip is attached as indicated in the other figures, then the doubly folded edge provides the reinforcement. If the base channel is convex, as shown in Figure 1, the nail head forms a countersunk recess within which the nail head seats.

Having thus described my invention, what I claim as new and desire to secure by Letters Patent, is:—

1. A weather strip having a plurality of reinforced attaching portions.

2. A weather strip having a plurality of reinforced attaching portions comprising a channeled base and folded over edges.

3. A weather strip comprising a channeled base and resilient legs extending at obtuse angles to said base, said channeled base having a slightly convexed surface.

4. A weather strip having parallel obtuse angle bends both in the same direction along its middle affording a relatively wide stiffened middle bearing portion, and having its longitudinal edge portions folded inward, forming two-ply rims, each affording a relatively wide stiffened bearing portion, whereby said strip may be non-tiltably attached by fastening means passed through any one of the three bearing portions, said strip being single-ply and substantially straight from each edge bearing portion to its middle bearing portion, to provide the effective resiliency of the strip.

5. A weather strip having parallel obtuse angle bends both in the same direction along its middle, and being arched in said direction between said bends, whereby said bends form transversely spaced lines of bearing, and having its longitudinal edge portions folded inward, forming two-ply rims, each affording a relatively wide stiffened bearing portion, whereby said strip may be non-tiltably attached by fastening means passed through either one of the edge bearing portions or through the arched middle portion, said strip being single-ply and substantially straight from each edge bearing portion to the respective line of bearing, to provide the effective resiliency of the strip.

6. A weather strip having parallel obtuse angle bends both in the same direction along its middle, and being arched in said direction between said bends, whereby said bends form transversely spaced lines of bearing whereby the strip may be non-tiltably attached by a headed fastening element passed through the arched portion, in which portion the head of the element may be sunk, said strip having its longitudinal edges bent to form stiffened convex bearing surfaces and being substantially straight from each of said edges to the respective line of bearing, to provide the effective resiliency of the strip.
